UNITED STATES PATENT OFFICE.

FREDERICK WILLIAM DURHAM AND JAMES DIXON CHURCHILL, OF LONDON, ENGLAND.

APPARATUS FOR EFFECTING INTERMITTENT ACTION OF FOG AND OTHER SIGNALS.

SPECIFICATION forming part of Letters Patent No. 336,041, dated February 9, 1886.

Application filed July 10, 1884. Serial No. 137,360. (No model.) Patented in England December 31, 1883, No. 5,966.

To all whom it may concern:

Be it known that we, FREDERICK WILLIAM DURHAM and JAMES DIXON CHURCHILL, citizens of England, both residing at Leadenhall Street, in the city of London, England, have invented new or Improved Apparatus for Effecting Intermittent Action of Fog and other Signals, (for which we have obtained a Patent in Great Britain, No. 5,966, dated December 31, 1883,) of which the following is a specification.

It is usual to provide in steam-vessels audible fog-signals, which are sounded at regular intervals, but variable at pleasure.

15 Our invention relates to means of effecting automatically the intermittent action of such signals, the apparatus which we employ for this purpose being so arranged that the interval between successive signals and the duration of each signal can be varied as desired.

20 We will describe this apparatus, referring to the accompanying drawings, Figure 1 being a sectional plan of the two steam-cylinders and the cataract-cylinder which we employ, 25 Fig. 2 being a side view of the cataract-cylinder with the cover of its valve-box removed.

A is a cylinder having a slide-valve, B, which alternates the admission and emission 30 of steam at each end of the cylinder, this slide being worked by the steam-pressure in the manner similar to that employed in several kinds of direct-acting pumping-engines. The piston of the cylinder A is directly connected 35 with the piston of a cataract-cylinder, C, which is charged with water, oil, or other suitable liquid. The two ends of the cataract-cylinder C communicate with each other by passages governed by a valve, D, and a plug, 40 F, having a slit, E, the opening of each of which can be regulated by a screw, so that the strokes of the cataract-piston can be timed as desired, the stroke in either direction being made to occupy a longer or shorter period, 45 according as the communicating passage is more or less throttled by the adjustment of the valve and slit.

The passages referred to, as illustrated, are, in connection with the valve-box J, shown as 50 attached to the side of the cataract-cylinder

and communicating with the end of the cylinder through the channels indicated by dotted lines in Fig. 2. The valve-box J is divided into an upper and a lower chamber by a partition, I, which has two openings, one 55 for the valve D and the other for the plug F. The plug F is formed with screw-threads, so as to be raised and lowered to regulate the extent of the slit-opening for the passage of the liquid, and adjusting-screw D' regulates 60 the extent of play of valve D, against the top of which the screw will bear.

Each end of a third cylinder, G, communicates with an end of the cylinder A, and this cylinder is fitted with a piston, the rod H of 65 which is connected by a cord, chain, or rod to the stop cock or valve (not shown) that governs the passage to a steam horn or whistle. The piston of the cylinder G is preferably provided with buffer-springs K, to lessen the 70 shock at each end of its stroke.

The action of the apparatus is as follows: Steam being admitted to the slide-case of the cylinder A, and the slide being, if necessary, shifted toward one end of its stroke by means 75 of a pushing-arm, a, worked by an external handle, the steam passes to one end of the cylinder A, and also to the corresponding end of the cylinder G, causing the piston of the latter to move rapidly to the one end or the 80 other of its stroke, and so as to open or close the passage to the alarm. While the piston of cylinder G is maintained by the steam-pressure at the end of its stroke, the piston of cylinder A makes its stroke more or less slowly, 85 as determined by the resistance offered to the movement of the cataract-piston due to the adjustment of the cataract-valves. As the piston of cylinder A completes its stroke, it strikes against and opens the valve b at the end of 90 the cylinder, thus permitting the escape of steam, relieving the pressure on the piston at one end of the slide-case, whereupon the slide is shifted and the pistons of cylinders G and A, respectively, have their movements 95 reversed, the former rapidly and the latter at the rate, more or less slow, determined by the adjustment of the cataract-valve which governs the speed of this stroke.

Obviously by extending the space between 100

the cylinders A and C and providing suitable tappets on the rod which connects their pistons the slide B may be worked by these tappets, as, for instance, in the ordinary, "Cameron 5 Steam-Pump;" also, the piston-rod H, instead of being connected to the cock or valve of an audible alarm-signal, might be connected to the screens or colored glasses of lantern-lights, so as to give or alternate visible signals.

10. In cases where the backward and forward strokes of the cataract-piston may be of equal duration, the adjustable slit E would suffice to regulate that duration; but as it is usually necessary to give a signal for a very short 15 time, and to have a considerable interval between successive signals, we add the valve D, to give regulated passage for the liquid in the one direction, in addition to that given by the slit E. When the cataract-piston is making 20 its stroke to the left, the valve D closes automatically, and the only passage for the liquid is by the slit E; but when the cataract-piston is making its stroke to the right, the passage consists of that by the slit, with the addition 25 of the opening of the valve D as far as permitted by its adjusting-screw. The left-hand stroke being slowly made would then determine the interval between successive sig-

nals, and the more rapid right-hand stroke would determine the duration of the signal 30 itself.

Having thus described the nature of our invention and the best means we know for carrying the same into practical effect, we claim—

35 The combination of the steam-cylinder A, its piston, the movable slide-valve B, the cataract-cylinder C, having its ends in communication, the adjustable valve or valves controlling the communication between the ends 40 of the cataract-cylinder, the cylinder G, supported upon and in communication with the opposite ends of the steam-cylinder A, a piston in said cylinder G, and a rod attached to such piston for connecting with a signal, substantially as described.

In testimony whereof we have signed our names to this specification, in the presence of two subscribing witnesses, this 25th day of June, A. D. 1884.

FREDERICK WILLIAM DURHAM.
JAMES DIXON CHURCHILL.
